UNITED STATES PATENT OFFICE.

LYNN A. WILLIAMS, OF EVANSTON, ILLINOIS.

VACUUM-TANK.

1,349,993.

Specification of Letters Patent. Patented Aug. 17, 1920.

Application filed June 14, 1918. Serial No. 239,946.

To all whom it may concern:

Be it known that I, LYNN A. WILLIAMS, a citizen of the United States, residing at Evanston, in the county of Cook and State 5 of Illinois, have invented a certain new and useful Improvement in Vacuum-Tanks, of which the following is a full, clear, concise, and exact description, reference being had to the accompanying drawings, forming a 10 part of this specification.

This invention relates to improvements in vacuum tanks, and is especially concerned with improvements on the type of tank disclosed in the application of Clifford C. 15 Bradbury, Serial No. 229,347, filed April 18, 1918, which is designed to be used for supplying carbureters with fuel from a main fuel tank lying below the level of the carbureter fuel chamber.

20 The objects of this invention are:

1st. To provide a vacuum tank comprising a storage receptacle and a suction receptacle supported above the storage receptacle and in communication therewith,

25 through an apertured member with a valve structure for controlling the communication between the two receptacles which will operate with a very small reduction in pressure in the suction receptacle; and

30 2nd. To provide a vacuum tank of the type described with a valve mechanism for controlling communication between the receptacles which will operate with a minimum reduction of pressure in the suction receptacle, but which at the same time will open sufficiently, to provide sufficient portage to permit comparatively large particles of dirt or other solid materials to be discharged from the suction receptacle into the 35 storage receptacle.

40 Other objects will appear as the description progresses, reference being had to the accompanying drawings in which,

45 Figure 1 is a longitudinal vertical section through a tank embodying my invention;

Fig. 2 is a sectional detail taken on a plane at right angles to the plane of Fig. 1;

50 Fig. 3 is an enlarged sectional detail taken on the same plane as Fig. 2 and showing certain details of the structure of my improved valve mechanism; and

Fig. 4 is a transverse section taken upon line 4—4 of Fig. 1.

55 In the several views similar characters of reference refer to similar parts, and Fig. 4

is taken looking in the direction of the small arrows.

In tanks of the type to which my invention relates it is desirable that the valve controlling communication between the suction chamber and the storage receptacle should respond to the slightest reduction in pressure in the suction receptacle in order that there will be no delay in the operation of the device to replenish the fuel withdrawn from the storage receptacle and in order that the device will operate when the engine is running at low speeds. It is also desirable that the valve mechanism for controlling communication between the two receptacles should be of such a character as to provide sufficient clearance or portage to allow comparatively large pieces of dirt or other solid material which may be drawn into the suction receptacle from the main 60 storage reservoir to pass into the storage receptacle and not interfere with the operation of the valve controlling communication between the two receptacles. 65

In the accompanying drawings I have 70 illustrated my invention in connection with the tank structure disclosed in the application of Clifford C. Bradbury, referred to above, and will, therefore, only describe in a brief manner those features of the tank 75 which form no part of my invention.

Referring to the drawings, the reference character 10 indicates the suction receptacle and the reference character 11 indicates the storage receptacle. The adjacent open ends 80 of these receptacles are flanged outwardly, as indicated at 12 and 13, respectively, and secured together by means of bolts 14, a partition member 15 being interposed between the flanges of the two receptacles to close 85 the flanged ends thereof. The upper or closed end of the suction receptacle is provided with a central aperture which receives a valve body 16, the inner end of which is screwthreaded and supports a plate 17 in 90 such a position that its outer periphery forms a sealing contact with an inwardly projecting annular rib 18. The space between the plate 17 and the closed end of the receptacle 10 forms an overflow space which 95 is connected with the storage receptacle 11 by means of a tube 19 (see Fig. 2). The plate 17 is locked to the lower end of the valve body by means of a nut 21. 100

The inlet coupling 22 extends loosely 110

through the closed end of the receptacle 10 and discharges through an opening in the plate 17 into the suction receptacle, a deflector plate 23 being employed to cause 5 the fuel to be discharged against the adjacent wall of the suction receptacle so as to prevent it from discharging upon the float 24, which, as will be described later, controls certain valve mechanism. As will be 10 understood by those skilled in this art the member 22 is connected by means of a pipe or other conduit with the main fuel reservoir which lies below the level of the carbureter and the vacuum tank, the main fuel 15 reservoir being open to the atmosphere so that the fuel therein is subject to atmospheric pressure.

The valve body 16 is provided with a valve chamber 25 with which the ducts 26, 20 27, and 28 communicate. A double faced valve 29 controls the passage of air through the ducts 26, and 27. The duct 26 opens to atmosphere and the duct 27 is connected by means of the union 30 with any suitable 25 source of suction. When the valve is in the position shown in Fig. 1 the suction chamber is in communication with the source of suction and the pressure in the suction chamber is reduced, but when the 30 valve moves downwardly so as to close the duct 27 and open the duct 26 the suction chamber is open to atmosphere.

The means for controlling the valve 29 comprises a valve stem 31 which extends 35 downwardly through the valve body and into the suction chamber, the lower end of the valve stem being reduced in cross section as shown at 32 to provide a shoulder 33 with which one end of the valve lever 40 34 co-acts to raise the valve to the position shown in Fig. 1. The opposite end of the valve lever 34 is pivotally mounted, as indicated at 35, intermediate the ends of the float lever 36. The upper end of the float 45 lever 36 is pivotally supported on a pivot rod 37 which in turn is supported by a bracket 38 secured to the plate 17.

As described in the application of Clifford C. Bradbury, above referred to, the 50 valve lever 34, the float lever 36, and the bracket 38 are all bifurcated at their adjacent ends so that the tension spring 39 may operate freely between the bifurcations of these levers. One end of the spring 39 is 55 secured adjacent the free end of the valve lever 34 and the other end thereof is secured to the pivot rod 37. The pivot points of the valve lever 34 and the float lever 36 are so arranged relative to each other 60 and to the axis of the spring 39 that when the axis of the spring 39 lies above the pivot point 35 the valve 29 will be held in its uppermost position, but when the float 24 is lifted until the pivot point 35 is raised 65 above the axis of the spring 39 the tension

of this spring will cause the free end of the valve lever 34 to snap downwardly and thereby permit the valve 29 to drop.

The partition member 15 is provided with a central orifice which receives the upper 70 end of a discharge pipe 40 which establishes communication between the suction receptacle and the storage receptacle. The lower end of the pipe 40 has formed therein an annular groove 41 which receives the 75 spurs 42 of the upwardly extending arms 43 of a clip member. Secured to the lower side of the clip member by means presently to be described is a priming cup 44. A disk valve 45 confined between the arms 43 80 of the clip member provides means for closing the lower end of the pipe 40.

The structure thus far described is similar to that disclosed and claimed in the application of Clifford C. Bradbury referred 85 to above. In that application, however, the disk valve for closing the lower end of the pipe corresponding to the pipe 40 of this application merely slides up and down between the arms 43. With such an arrangement when the valve corresponding to the valve 45 is in its lowermost position it requires an undesirable reduction in pressure in the suction tank 10 to close the disk valve. In order to overcome this objection I provide the lower side of the disk valve 45 with 90 a central ring shaped projection 46 which receives the upper rounded end of a pin 47. The pin 47 is provided with an annular shoulder 48 and its lower end is swaged 100 over to form a head 49 for securing the priming cup 44 to the clip member. The depression formed in the lower side of the disk 45 is sufficiently wide to permit the disk to pivot or tilt about the end of the 105 pin 47 so that at one point, as illustrated at 50, the upper side of the disk valve will contact with the lower edge of the pipe 40. With such a construction the valve structure will have as great a portage for 110 fuel as a valve structure in which all points of the lower end of the pipe 40 are equally spaced from the adjacent surface of the disk, but the opening at the point 51 will permit the discharge of particles of dirt or 115 other material substantially twice as large as would be permitted by a valve structure having the same portage but in which all points on the lower edge of the pipe 40 are equally spaced from adjacent points on 120 the surface of the disk valve.

There is another advantage to be gained by this structure and that is that the disk valve may tilt about the pin 47 and thus bring different points on the surface of the 125 valve in contact with different points on the adjacent lower edge of the pipe 40, thereby permitting small particles of dirt to be washed from the upper surface of the disk by the flow of fuel thereover so as 130

not to interfere with the closing of the valve. A still further advantage to be gained by this structure is due to the fact that in case the level of the fuel in the 5 storage receptacle 11 should fall below the level of the priming cup 44 and due to the tilting of the motor vehicle upon which the tank is installed the fuel should be displaced from the priming cup 44, nevertheless 10 wedge shaped films of oil will be retained between the lower edge of the pipe 40 and the upper surface of the disk 45, these films extending in the opposite direction from the point 50. These films will have a 15 considerable surface tension which will tend to pull the disk 45 upwardly against the lower end of the pipe 40 and will thereby assist any suction produced in the chamber 10 to close the valve 45. On account 20 of this construction it will not require as great a reduction of pressure in the suction chamber 10 to close the valve 45 as it would if the lower edge of the pipe 40 was equally spaced at all points from 25 the adjacent surface of the valve 45.

It is believed that the operation of my improved structure will be clear to those skilled in this art from the above description, and further details thereof are believed 30 to be unnecessary. It is to be understood, however, that although I have described my invention in connection with the vacuum tank disclosed in the application of Clifford C. Bradbury, above referred to, 35 that it is capable of being used with vacuum tanks of different types, and, furthermore, that it is not limited to use in a vacuum tank employing the priming cup 44 described above.

40 While I have described the details of the preferred embodiment of my invention it is capable of other adaptations and modifications within the scope of the appended claims.

45 Having thus described my invention what I claim as new and desire to secure by Letters Patent of the United States is:

1. A vacuum tank comprising a storage receptacle, a suction receptacle located above 50 said storage receptacle, a pipe for affording communication between said receptacles extending downwardly in said storage receptacle and having its lower end in a substantially horizontal plane, a disk valve 55 for closing the lower end of said pipe having a central ring shaped projection on the lower side, and a pin having a rounded head received in said ring shaped projection to pivotally support said disk valve adjacent the lower end of said pipe.

60 2. A vacuum tank comprising a storage receptacle, a suction receptacle located above said storage receptacle, a pipe for affording communication between said receptacles extending downwardly in said storage recep-

tacle and having its lower end in a substantially horizontal plane, a disk valve for closing the lower end of said pipe having a central ring shaped projection on the lower side, and a pin received in said ring shaped projection to pivotally support said disk valve adjacent the lower end of said pipe. 70

3. A vacuum tank comprising a storage receptacle, a suction receptacle, a pipe for affording communication between said receptacles extending downwardly and discharging into said storage receptacle and having its discharge end in a substantially horizontal plane, a valve for closing the discharge end of said pipe, and fixed means for supporting said valve so that it may contact with any, but only one, point on the periphery of the lower end of said pipe. 75

4. A vacuum tank comprising a storage receptacle, a suction receptacle, a pipe for affording communication between said receptacles extending downwardly and discharging into said storage receptacle and having its discharge end in a substantially horizontal plane, an imperforate valve for closing the discharge end of said pipe, and means for supporting said valve so that it may contact with only one point on the 80 periphery of the lower end of said pipe. 85

5. A vacuum tank comprising a storage receptacle, a suction receptacle, a pipe for affording communication between said receptacles extending downwardly and discharging into said storage receptacle and having its discharge end in a substantially horizontal plane, a valve for closing the discharge end of said pipe, and fixed means for supporting said valve so that it may contact with any single point on the periphery of the lower end of said pipe. 95

100 6. A vacuum tank comprising a storage receptacle, a suction receptacle above said storage receptacle, a member provided with an aperture for affording communication between said tanks, the edges of said aperture lying in a substantially horizontal plane, a valve for closing said aperture, and fixed means for tiltably supporting said valve adjacent said aperture so as to tilt in different directions. 110

115 7. A vacuum tank comprising a storage receptacle, a suction receptacle, a member provided with an aperture for affording communication between said tanks, a valve for closing said aperture, and fixed means for tiltably supporting said valve adjacent said aperture so as to tilt in different directions. 120

125 8. A vacuum tank comprising a pair of receptacles, an apertured member for affording communication between said receptacles, a valve for closing said aperture, and fixed means for supporting said valve so as to suc-

cessively contact with any of a plurality of points on said apertured member.

9. A vacuum tank comprising a pair of receptacles, an apertured member for affording communication between said receptacles, and means for closing the aperture in said member comprising an imperforate valve, and means for pivotally supporting said valve so as to contact with the edge of said

10 aperture at but a single point.

10. A vacuum tank comprising a pair of receptacles, means for affording communication between said receptacles so as to permit the contents of one receptacle to discharge

15 into the other receptacle, and means for causing the discharge in said last named receptacle to take place in different directions.

11. A vacuum tank, comprising a storage receptacle and a suction receptacle, a passage affording communication between said receptacles and a universally tilttable valve for controlling said passageway.

12. A vacuum tank comprising a storage receptacle, a suction receptacle supported

25 above said storage receptacle, a pipe for affording communication between said re-

ceptacles extending downwardly in said storage receptacle and having its discharge end in a substantially horizontal plane, and a universally tilttable valve adjacent said pipe for closing the lower end thereof.

13. A vacuum tank, comprising a storage receptacle, a suction receptacle, a pipe for affording communication between said receptacles extending downwardly in said storage receptacle and having its discharge end in a substantially horizontal plane, a disk valve for closing the lower end of said pipe and means for permitting universal tilting of said valve.

14. A vacuum tank comprising a storage receptacle and a suction receptacle, a pipe affording communication between said receptacles and a valve for closing said pipe, said valve not being engaged by any supporting means when it closes said pipe.

In witness whereof, I hereunto subscribe my name this 3d day of June, A. D. 1918.

LYNN A. WILLIAMS.
